CANTILEVER COLUMN ASSEMBLAGE FOR
CRUSHERS

Harvey H. Rumpel, Milwaukee, Wis., assignor to
Smith Engineering Works, Milwaukee, Wis., a
corporation of Wisconsin

Application February 14, 1944, Serial No. 522,275

8 Claims. (Cl. 241—208)

1

The present invention relates in general to improvements in the crushing art, and relates more specifically to improvements in the construction and operation of head supporting columns for gyratory crushers of the general type shown in my prior Patents No. 2,158,779, granted May 16, 1939, and No. 2,409,391, granted October 15, 1946, and wherein the crushing head is supported by and is gyratable about a fixed upstanding column with the aid of a rotary eccentric interposed between the head and column.

The primary object of my present invention is to provide an improved gyratory crusher of the above described type, which is simple and durable in structure, and which is also highly effective in use.

When constructing gyratory crushers of the type wherein the conical crushing head is movably supported solely by and is gyratable about a fixed upstanding column or shaft by means of a rotary eccentric disposed between the column and the head, it is of primary importance that the column be firmly mounted or supported. In some cases the head supporting column is formed integral with the supporting frame of the crusher, and in others the column is merely an upright stub shaft secured to the main frame; but the latter mode of producing and mounting these columns is preferable both because it facilitates original manufacture, and it also makes possible removal or replacement of the head supporting shafts.

It is therefore a more specific object of my present invention to provide an improved gyratory crusher of the above specified general type, wherein the column is constructed in the form of a simple and readily removable stub shaft capable of resisting considerable and varying pressures without becoming loosened, and which may be rigidly and firmly secured to the main frame of the crusher or removed therefrom, in an expeditious manner either in the shop or in the field, and with the aid of ordinary tools and equipment.

Since the upstanding head supporting columns of these crushers, are supported only at their lower ends, it is also extremely desirable to avoid the application of excessive lateral pressures during normal crushing, against the upper laterally unsupported portions thereof; and to construct the head and column assemblages so that the major portion of the lateral crushing pressures are automatically applied to ample bearing surfaces of the frames and columns near the base or lower portions of the latter. This 55

2

is true whether the columns are formed integral with the frame or as separate shafts, and practically all prior crushers of this type have lacked either sufficiently extensive bearing surfaces, or proper distribution of the lateral crushing pressures relative to the columns, or proper anchorage of the columns when formed as separable elements.

Hence, it is also a more specific object of my invention to provide an improved gyratory crusher head and column assembly wherein bearing surfaces of ample size are provided, and in which the crushing pressures are more effectively distributed and applied to the supporting structure so that the major lateral pressures will act upon the column near its supporting base and remote from its laterally unsupported upper extremity, while the column remains fixedly anchored thereby eliminating excessive heating and consequent wear.

It is furthermore desirable in gyratory crushers of the type having the head gyratable about a fixed column or stub shaft with the aid of an intervening rotary eccentric, to have the eccentric provided with an inner bore formed coaxial and coacting directly with the column, while the external eccentric surface which cooperates with a bore in the head, is formed concentric with an axis which intersects the column axis above the upper end of the column and of the crushing zone. Since the head must be freely rotatable about the eccentric, besides being gyratable thereby, and is also supported solely from the upper extremity of the fixed column or shaft, it is necessary to provide a suitable thrust bearing between the head and column which will permit such free gyration and rotation of the head. While various forms of such thrust bearings have heretofore been proposed, these prior devices were either too complicated, or they were relatively difficult to construct and to assemble, or they were rather inefficient and insufficiently durable in performance.

It is therefore also a more specific object of my invention to provide an improved thrust bearing between the head and supporting column or fixed shaft of a gyratory crusher wherein the head is gyratable by an eccentric interposed between the column and the head, which is extremely simple in construction, which may be readily manufactured and assembled, and which is moreover highly efficient and durable in use.

These and other specific objects and advantages of the present invention will be clearly apparent from the following detailed description.

A clear conception of the several features constituting my present invention, and of the mode of manufacturing, of assembling, and of operating gyratory crushers embodying the improvement, may be had by referring to the drawing accompanying and forming a part of this specification, wherein like reference characters designate the same or similar parts in the various views.

Fig. 1 is a central vertical section through a typical gyratory crusher embodying my present invention; and

Fig. 2 is a fragmentary central vertical section through a modified mounting for the head supporting column of such a gyratory crusher.

Although the present invention has been shown and described herein as being especially applicable to a particular type of gyratory crusher especially adapted for fine crushing and having a conical crushing head cooperating with a conical outwardly flaring concave to provide a flaring crushing zone, it is not my desire or intent to thereby unnecessarily limit the invention which may also be advantageously applied to other types of crushing machines having differently shaped crushing heads and concaves.

My improved gyratory crusher shown in the drawing, comprises in general a sturdy main frame 4 having a massive upstanding column or shaft 5 rigidly but removably secured to a lower hub portion 6 of the frame; an eccentric 7 having an annular inner surface or bore 8 journalled for rotation upon the outer side surface of the column shaft 5 and also having an outer annular surface 9 the central axis of which is inclined relative to and intersects the central axis of the bore 8 above the top of the fixed shaft 5; a frusto-conical crushing head 10 having a central bore rotatably engaging the outer eccentric surface 9, the head being provided with an integral top portion 11 spanning but spaced from the top of the shaft 5 and eccentric 7; a thrust block 12 interposed between the head portion 11 and the top of the shaft 5 for directly supporting the head upon the column; an annular crushing concave 13 carried by the main frame and cooperating with the crushing head 10 to provide a downwardly extending outwardly flaring crushing zone 14; and crusher driving mechanism including an annular bevel gear 15 firmly secured to the eccentric 7 and meshing with a bevel pinion 16 carried by a counter-shaft 17 having thereon a driving pulley 18, and which is journalled for rotation in a bearing assemblage 19 also secured to the main frame 4.

It is of primary importance that the upstanding column shaft 5 which is laterally unsupported at its upper end and which constitutes the sole support for the weight of the crushing head 10, be firmly supported or mounted at its lower end within the frame hub portion 6. The hub portion 6 of the main frame 4 is rigidly integrally connected to the outer annular frame wall 20 by means of a series of radiating ribs 21 and a diaphragm 22 so as to provide ample space for delivery of the crushed material by gravity from the lower annular discharge opening of the crushing zone 14, thus providing a strong unitary frame assemblage. The hub portion 6 is provided with a downwardly tapered central bore 23, and the lower end 24 of the stub shaft 5 is similarly tapered; but the external diameters of the successive transverse portions of the shaft taper, are preferably slightly larger than the corresponding diameters of the hub bore 23 before

the shaft 5 is finally applied to the frame 4, in order to insure firm radial clamping of the shaft end 24 within the hub 6 when the column shaft 5 is finally positioned. This slightly enlarged tapered shaft end 24 may be snugly confined within the frame bore 23 either by heating the hub 6 so as to expand its bore 23 and by thereafter inserting the tapered shaft end 24 and shrinking the hub about the shaft, or by forcing the shaft end 24 longitudinally of its axis into the bore 23. The latter of these fastening methods is preferable when it becomes desirable to remove the column shaft 5 from the frame 4, and in either case it is also necessary to provide a stop or abutment surface on the shaft 5 in order to definitely place the shaft in a predetermined fixed position with respect to the main frame when finally applied thereto, and to prevent vertical components of the crushing pressures from driving the tapered lower end 24 of the shaft 5 into the frame bore 23 so as to create excessive radial pressures tending to burst the hub 6.

As shown in Fig. 1, the lower extremity or end surface 25 of the stub shaft 5 constitutes the stop or abutment, and this shaft end surface 25 must be brought into horizontal alinement with the lower transverse surface 26 of the frame hub 6, before the shaft 5 is rigidly and immovably positioned. This may be effectively accomplished by providing a lower jack plate 27 which may be firmly secured to the bottom of the hub 6 by means of studs and nuts 28, and by also providing several jacking studs 29 at the lower extremity of the shaft 5 and which pass through openings in the heavy plate 27. By applying jacking nuts 30 to these studs 29, the tapered shaft end 24 may be drawn into the hub bore 23 until the lower transverse surfaces 25, 26 coact with the plate 27 whereupon the shaft 5 will be firmly clamped in proper position. This assemblage of elements may obviously be readily dismantled so as to effect removal of the shaft 5, by merely releasing the nuts 30 and by subsequently driving the tapered end 24 out of the hub bore 23, and both the assembling and removal operations may obviously be carried on with ordinary tools.

While the transverse stop surface 26 in Fig. 1, is at the lower extremity of the bore 23 and shaft 5, this transverse may also be provided at the upper portion of the tapered shaft surface or end 24, as illustrated in Fig. 2. In the modification, the shaft 5 is provided at the upper portion of its tapered end 24, with an integral flange 31 which has a lower transverse surface adapted to contact an annular transverse surface 32' formed at the upper end of the hub bore 23, when the column shaft has been driven home. The lower extremity of the shaft 5 need not contact the jack plate 27 in the modified structure, and the collar flange 31 provides a seal at the top of the clamping joint when the parts are assembled. The modified fastening for the column shaft 5 may be assembled and released in the same manner as in Fig. 1, and both methods of attachment are perfectly satisfactory and provide a definite stop for properly positioning the stub shaft.

In order to protect the fixed column shaft 5 which is laterally unsupported at its upper end, against excessive lateral pressures during normal crushing, the gyratory and freely rotatable crushing head 10 and the crushing concave 13 should be so formed and cooperable with the supporting column, that the major lateral crushing pressures

are directed toward the shaft 5 near its mounting base. As shown, the concave 13 is provided with the usual renewable liner 32, and the head 10 is likewise provided with a renewable protecting mantle 33 which cooperates with the liner 32 to provide the downwardly directed and outwardly flaring annular crushing zone 14, and these protecting elements are preferably constructed to form a downwardly tapering upper crushing space 34 followed by a relatively parallel lower finishing or material sizing space 35 within the crushing zone 14. The upper extremity of the fixed column shaft 5 is located considerably below the upper inlet end of the crushing space 34 but above the upper end of the finishing space 35, and the crushing surfaces bounding the zone 14 are so directed that lateral crushing pressures directed perpendicularly thereagainst, are transmitted through the head 10 and eccentric 7 toward the lower fixed or anchored portion of the supporting shaft 5, and not against its upper laterally unsupported portion. In this manner the stub shaft 5 which is also constructed of such diameter that it will provide ample surface for proper distribution of and resistance to the crushing pressures, is subjected to the major lateral crushing components only near its lower anchored portion and will be less subject to loosening than if these pressures were repeatedly applied against the column top.

As previously indicated, the crushing head 10 is freely rotatable about the outer eccentric surface 9 and is gyratable by the eccentric 7 about the upstanding column shaft 5, and the upper end of the head above the integral supporting portion 11 thereof, may be sealed by a removable feed plate 36, while the lower part of the head may be caused to coact with an annular sealing member 37 through annular sealing bands 38 formed concentric with the central axis of the crushing head 10. The sealing member 37 is carried by the ring gear 15 which is secured to the eccentric 7 near the main eccentric supporting thrust bearing 39, and has a sealing ring 40 which coacts with an inner cylindrical surface of the main frame 4 and which is protected by other annular sealing bands 41 interposed between the member 37 and frame 4. The ring 40 and bands 41 are formed concentric with the central axis of the column shaft 5 and eccentric bore 8, and this assemblage of sealing elements provides an effective seal for the eccentric 7 which does not interfere with the free relative rotation of the head and its gyrating eccentric.

In order to permit such free rotation and gyration of the crushing head 10 relative to the fixed column shaft 5, provision must also be made for permitting universal swinging and lateral sliding of the head 10 relative to the upper end of the column upon which the weight of the head is supported through the thrust bearing or block 12. This is accomplished by providing the column shaft 5 above the upper end of the eccentric 7, with a concave spherical zone surface 42 which slidably and rockably coacts with a similar surface formed on the bottom of thrust block 12, both of these spherical zone surfaces being generated about the point of intersection of the head and column axes disposed well above the crushing zone 14. The integral upper portion 11 of the crushing head 10, which spans the thrust plate 12 and the top of the column shaft 5, is provided with a circular central recess within which a wearing plate or disk 43 is confined against rotation by one or more dowel pins 44, and this wearing disk 43 has a lower plane surface 45 which

slidably engages the upper plane surface of the thrust block 12 below the upper inlet end of the crushing zone 14. The wearing disk 43 reacts against a series of circular shims 46 one or more of which may be removed or added so as to vary the vertical position of the crushing head 10 relative to the rotary sealing member 37 in order to insure proper functioning of the sealing bands 38, 41 at all times, and to also compensate for wear between the thrust block 12 and the adjacent elements. This assemblage obviously provides a bearing for universally movably supporting the weight of the crushing head 10 and mantle 33, which is simple and effective and which also permits convenient adjustment of the head relative to the column shaft 5 and rotating sealing member 37.

The details of construction of the crushing concave supporting and adjusting mechanism, 20 constitute no important part of my present invention, but the annular concave 13 with its renewable liner 32, are tiltably mounted upon an annular upper projection 47 formed upon a vertically adjustable supporting ring 48 which is carried by and is adapted to be locked to the outer wall 20 of the main frame 4, by means of an externally threaded locking wedge ring 49. The supporting ring 48 also carries a reaction spider 50 through bolts 51, and compression springs 52 are interposed between the top of the concave 13 and the normally fixed spider and serve to prevent tilting of the concave 13 upon the projection 47 during normal operation of the machine. A feed hopper 53 may also be mounted upon the concave 35 13 in line with the upper inlet opening of the crushing zone 14, and when abnormally hard material enters the crushing chamber, the springs 52 are adapted to permit the concave 13 to tilt and to thereby relieve excessive pressures.

40 During normal operation of the improved gyratory crusher, the drive shaft 17 is being rotated by power applied to the pulley 18, thereby imparting relatively rapid rotation to the eccentric 7 through the pinion 16 and ring gear 15. 45 The eccentric will then revolve about the fixed column 5 and upon the thrust bearing 39, and the rotation of the eccentric 7 will produce rapid gyration of the crushing head 10 and its mantle 33, relative to the concave 13 and liner 32, while 50 at the same time permitting free relative rotation of the head 10 with respect to the outer eccentric surface 9. The material which is to be crushed, is admitted to the upper end of the crushing zone 14 from the supply hopper 53, and is subjected to a rapid succession of crushing impulses 55 while it gravitates downwardly through the crushing zone 14. In this manner the admitted material is gradually reduced in size and gravitates toward the final sizing space 35 wherein it 60 is reduced to uniform size and from which it is finally delivered from the crushing zone 14. The final product then gravitates from within the crushing frame 4 over the diaphragm 22 in a well known manner. While the crusher is thus operating, lubricant should be constantly forced through the passages in the column shaft 5 and should be distributed along grooves in the thrust plate 12, eccentric 7, head 10, and thrust bearing 39 so as to constantly provide ample lubrication 65 for the various bearing surfaces of the machine, and the seals afforded by the sealing member 37, sealing ring 40, and sealing bands 38, 41 must be maintained in tight condition so as to prevent foreign matter from entering the lubricating ducts.

During this normal operation of the crusher, the head 10 will naturally be subjected to varying pressures of relatively high intensity, and by virtue of the improved mounting of the fixed column shaft 5, and of the head 10 and mantle 33, the column shaft will effectively resist these pressures without danger of having the same become loose. The clamping fit which is provided between the lower shaft end 24 and the frame hub 6, makes it possible to maintain a rigid anchorage for the upstanding column shaft 5, and the formation of the crushing surfaces of the head 10 and mantle 33 so that the major lateral crushing pressures are directed toward the lower portion of the supporting shaft 5, assists the anchorage provided by the lower tapered end 24, in avoiding possible loosening of the shaft. The disposition of the upper thrust bearing plate 12 below the upper inlet opening of the crushing zone 14, also avoids the application of undesirable high pressures against the upper laterally unsupported portion of the column shaft 5, and this shaft is thus amply protected against undesirably high lateral pressures. The shaft 5 may however be readily removed from the frame hub 6 by merely releasing the jack nuts 30 and forcing the shaft end 24 out of the bore 23, and by forming the spherical socket or concave surface 42 directly in the upper extremity of the shaft 5, the thrust bearing assemblage for supporting the weight of the head 10 is greatly simplified. The provision of the shims 46 between the wearing disk 43 and the upper head portion 11, makes it possible to vertically adjust the head 10 to some extent in order to compensate for wear, but the primary adjustment for varying the size of the crushed product should be effected with the aid of the adjusting wedge ring 49. The entire assemblage besides being sturdy and compact, may be readily manufactured and adjusted to meet various operating conditions, and may obviously be advantageously utilized in crushers adapted both for fine crushing and for relatively coarse crushing.

From the foregoing detailed description it will be apparent that my present invention provides various improvements in the construction and operation of gyratory crushers of the type wherein the head is rotatably supported by and gyrotable about a fixed column, whereby the durability and efficiency of such structures is enhanced to a maximum. The improved anchoring mechanism for fixedly mounting the upstanding column or shaft 5, will positively prevent possible loosening of this column during normal operation while still permitting convenient removal thereof. The formation of the column 5 and head 10 furthermore provides a durable structure and protects the column anchorage against possible loosening by directing the major lateral crushing pressures against the column near its fixed base; and the improved thrust bearing for transmitting the weight of the head against the upper extremity of the column shaft 5 may be readily manufactured and permits free rotation and gyration of the crushing head 10 without undesirable interference. The transverse positive stop surfaces for limiting the downward insertion of the tapered shaft end within the hub bore 23 shown in both Figs. 1 and 2, not only protect the frame hub 6 against the downward components of the crushing pressures, but also definitely positions the top of the shaft so that the head 10 and the sealing bands 38 at the lower end thereof will properly cooperate with the annular sealing

member 37; and the shims 46 which are provided between the thrust block 12 and the wearing disk 43, may be utilized to compensate for wear and to also insure proper functioning of the bands 38. The entire assemblage permits the production of an extremely compact and durable crusher wherein all parts are amply protected against undesirable loosening and consequent excessive wear, and the crushing assemblage may be manufactured at moderate cost and may be advantageously utilized for the reduction of various kinds of relatively hard materials to uniform final size.

It should be understood that it is not desired to limit this invention to the exact details of construction or to the precise mode of operation, herein shown and described, for various modifications within the scope of the claims may occur to persons skilled in the art.

I claim:

20. 1. In a crusher, a frame having thereon a rigid upstanding column the upper extremity of which is provided with a spherical depression, a thrust plate having a lower spherical zone surface coacting with and slidably laterally within said depression and also having an upper plane surface, an eccentric revolvable about said column, and a crushing head gyratable by said eccentric and having a lower inner plane surface coacting with and slidably laterally of said upper plate surface.
25. 2. In a crusher, a frame having thereon a rigid upstanding column the upper extremity of which is provided with a spherical depression, a thrust plate having a lower spherical zone surface coacting with and slidably laterally within said depression and also having an upper plane surface, an eccentric revolvable about said column, a crushing head gyratable by said eccentric and having a lower plane surface coacting with and slidably laterally of said upper plate surface, and
30. 35. 3. In combination, a frame having thereon a rigid upstanding cylindrical column the upper extremity of which has a spherical zone surface formed directly thereon, a thrust plate having a lower spherical zone surface coacting with and rockable upon said column surface and also having an upper plane surface, an eccentric having a bore journalled for rotation upon said column and being provided with an outer annular surface disposed eccentrically of said bore, and a crushing head having a bore coacting with said outer eccentric surface and being provided with a lower plane surface at the upper inner end of its bore which coacts with and is slidable laterally upon said upper plane plate surface.
40. 45. 4. In combination, a frame having thereon a rigid upstanding cylindrical column the upper extremity of which has a spherical zone surface formed directly thereon, a thrust plate having a lower spherical zone surface coacting with and rockable upon said column surface and also having an upper plane surface, an eccentric having a bore journalled for rotation upon said column and being provided with an outer annular surface disposed eccentrically of said bore, a crushing head having a bore coacting with said outer eccentric surface and being provided with a lower inner plane surface at the upper end of its bore which coacts with and is slidable laterally upon said upper plane plate surface, and shims insertible between said head and said plane head surface for varying the elevation of said head relative to said column.
50. 55. 5. In combination, a frame having a rigid up-

standing column provided with an annular guide bearing surface and with a spherical concavity at its top, an eccentric journalled for rotation on said guide bearing surface and having an outer annular surface the central axis of which intersects the generating center of said spherical concavity, and a crushing head freely rotatable about said outer eccentric surface and being gyratable by said concentric relative to said column, said head having a plane portion spanning the said column concavity, and a thrust plate interposed between said plane head portion and said concavity.

6. In a gyratory crusher, a frame having an integral lower hub provided with a downwardly tapered bore and also having a rigid transverse stop surface associated therewith at an end of the hub, a column having an extensive upper bearing portion and a lower downwardly tapered end portion adapted to snugly fit said hub bore and also having a rigid transverse stop surface at the corresponding end of its tapered portion, a pulling device coacting with said frame and column near the bottom of said hub for drawing said tapered column portion axially into said bore, said stop surfaces being located so that they will coact to prevent further axial movement of said tapered column portion into said hub bore when a predetermined outward radial pressure has been attained within the hub and said tapered frame bore and column portion constituting the sole means of preventing lateral displacement of said column bearing portion relative to the frame, an eccentric journalled for rotation upon said bearing portion, a crusher head coacting with said eccentric, and means for rotating said eccentric to gyrate said head about said column.

7. In a gyratory crusher, a frame having an integral lower hub provided with a downwardly tapered bore and also having a rigid transverse stop surface at the lower end of said bore, a column having an extensive upper bearing portion and a lower downwardly tapered end portion adapted to snugly fit said hub bore and also having a rigid transverse stop surface at the lower end of said tapered portion, a pulling device coacting with said frame and column near the bottom of said hub for drawing said tapered column portion downwardly into said bore, said stop surfaces being located so that they will coact to prevent further downward movement of said tapered column portion into said hub bore when a predetermined outward radial pressure has been attained within the hub and said ta-

- pered frame bore and column portion constituting the sole means of preventing lateral displacement of said column bearing portion relative to the frame, an eccentric journalled for rotation upon said bearing portion, a crusher head coacting with said eccentric, and means for rotating said eccentric to gyrate said head about said column.
8. In a gyratory crusher, a frame having an integral lower hub provided with a downwardly tapered bore and also having a rigid transverse stop surface at the upper end of said bore, a column having an extensive upper bearing portion and a lower downwardly tapered end portion adapted to snugly fit said hub bore and also having a rigid transverse stop surface at the upper end of said tapered portion, a pulling device coacting with said frame and column near the bottom of said hub for drawing said tapered column portion downwardly into said bore, said stop surfaces being located so that they will coact to prevent further downward movement of said tapered column portion into said hub bore when a predetermined outward radial pressure has been attained within the hub and said tapered frame bore and column portion constituting the sole means of preventing lateral displacement of said column bearing portion relative to the frame, an eccentric journalled for rotation upon said bearing portion, a crusher head coacting with said eccentric, and means for rotating said eccentric to gyrate said head about said column.
